Patented Apr. 16, 1968

210,813

PHONOGRAPH RECORD CARRIER

William V. Buchanan, 1175 York Ave.,
New York, N.Y. 10021

Filed June 20, 1966, Ser. No. 2,742

Term of patent 14 years

(Cl. D87—5)

FIG. 1

FIG. 2

FIG. 4

FIG. 3

FIGURE 1 is a top plan view of a phonograph record carrier, showing my new design.

FIGURE 2 is a front elevational view thereof.

FIGURE 3 is a side elevational view thereof.

FIGURE 4 is an exploded perspective view of the phonograph record carrier, with the cover removed from the base.

The dominant features of the design reside in the portions shown in full lines.

I claim:

The ornamental design for a phonograph record carrier, substantially as shown and described.
